**TANK FOR HOLDING REFLECTIVE-GRANULES
FOR A HIGHWAY CENTER-LINE MARKING
MACHINE**

Rufus W. Wilson, Huntingdon, Pa., assignor to Wald
Industries, Inc., Huntingdon, Pa., a corporation of
Pennsylvania

Filed Nov. 9, 1959, Ser. No. 58,284

Term of patent 14 years
(Cl. D55—1)

FIG. 1.

FIG. 2.

FIG. 3.

Figure 1 is a top plan view of a tank for holding reflective-granules for a highway center-line marking machine showing my new design.

Fig. 2 is a side elevational view thereof.

Fig. 3 is a bottom plan view thereof.

I claim:

The ornamental design for a tank for holding reflective-granules for a highway center-line marking machine as shown.
